UNITED STATES PATENT OFFICE

OLIVER C. K. HUTCHINSON, OF ALTON, ILLINOIS, ASSIGNEE TO OWENS-ILLINOIS GLASS COMPANY, A CORPORATION OF OHIO

MECHANISM FOR HANDLING GLASSWARE

Application filed December 1, 1930. Serial No. 499,180.

The present invention relates to improvements in mechanism for handling glassware such for example as bottles and jars. More particularly the invention is concerned with the removal and transfer of articles of glassware from the finishing molds of a forming machine to an annealing leir.

An object of the present invention is the provision of a continuously operating, completely automatic take-out and transfer mechanism capable of meeting the demands of the modern high speed glassware forming machines.

A further object is the provision of novel transfer mechanism by which bottles and the like articles, while quite hot and plastic, may be removed from the molds and transferred to an annealing leir without scratching or otherwise marring the articles. To this end the mechanism is arranged to engage the neck portion only, such portion ordinarily being chilled and set before the molds open, to an extent precluding scratching by the take-out mechanisms.

Other objects will be in part apparent and in part pointed out hereinafter.

In the drawings:

Fig. 1 is a plan view showing the operating position of the present invention.

Fig. 2 is a side elevation thereof.

Fig. 3 is a fragmentary plan view showing the relative positions of a pair of the transfer devices at the discharge end of their path of travel.

Fig. 4 is a vertical transverse sectional view with parts in elevation taken substantially along the line IV—IV of Fig. 1.

Fig. 5 is a sectional elevation showing one of the transfer devices about to remove articles from a finishing mold.

Fig. 6 is a sectional view taken along the line VI—VI of Fig. 5.

Fig. 7 is a detail elevation showing the operating connection between one of the take-out and transfer devices and the chain carrier.

Fig. 8 is a sectional view taken substantially along the line VIII—VIII of Fig. 7.

Fig. 9 is a sectional elevation taken substantially along the line IX—IX of Fig. 7

and showing in addition the supporting rails.

Fig. 10 is a vertical sectional elevation of the lower end of one of the article supporting devices showing the article grippers 55 and a portion of the mechanism for actuating the latter.

Fig. 11 is a plan view taken substantially along the line XI—XI of Fig. 10.

The forming machine 15 in conjunction with which the present invention is illustrated is more or less diagrammatically shown. In machines of this type, blanks or parisons are formed in blank molds (not shown) and transferred to portable finishing molds 16, in which said blanks are expanded to final form preparatory to removal from said finishing molds at the discharge station "D". These molds are arranged in an annular series and rotate continuously about a vertical axis so that they are brought in succession to said discharge station. The articles of glassware are removed from the finishing molds 16 and by suitable transfer mechanism 17 are carried to a cross conveyor 18 or 19 which in turn places the articles in row formation at the receiving end of an annealing leir 19 preparatory to being placed in said leir. This latter operation may be effected by any suitable mechanism 80 (not shown).

The take-out and transfer mechanism constituting the present invention, in more or less general terms, includes a series of tongs or grippers moving continuously in a closed path so that they are brought in succession to the discharge station "D" (this being the article engaging station for the take-out devices) where they supportingly engage finished articles in the finishing molds prior to and following opening of said molds, said tongs or grippers then carrying the articles to the article releasing station "E" where they are placed upon the cross conveyor 18. These stations are on opposite sides of the path of travel of the take-out and transfer devices. The transfer devices 20 move in synchronism with movement of the finishing molds 16 so that the molds and transfer devices are 100

in relative alignment at the discharge station "D".

The construction involved in the take-out and transfer mechanism comprises a series of take-out and transfer devices 20 suitably connected at uniformly spaced points to an endless carrier 21, such for example as a sprocket chain, which is trained over a pair of horizontally spaced sprockets 22. These sprockets 22 are mounted on vertical shafts 23, one of which is journaled in a bearing 24 at the outer end of an arm 25, extending horizontally from the upper end of a standard 26, while the other is journaled in a bearing 27 at the upper end of a vertical standard 28. These standards 26 and 28 also carry sets of horizontal arms 29 which support pairs of guide rails 30. These guide rails form a continuous track defining the path of travel of the carrier chain 21 on which the take-out and transfer devices 20 are supported. A hanger 31 at the upper end of a standard 32 supports intermediate portions of the guide rails 30. Each combined take-out and transfer device 20 comprises separable tongs or grippers 32 arranged at the outer end of a take-out arm 33 which is pivoted at one end to a carrier block 34, the latter suitably connected at its ends to the carrier chain 21. Each carrier block 34 is provided with guide rollers 35 which run in the guide rails 30 so that the block and elements carried thereby move with the chain in the closed path defined by the pair of guide rails. The take-out arm 33 is mounted for swinging movement in a vertical plane about a hinge pin 36 and a spacing sleeve 37, the latter maintaining the depending ears 38 in proper spaced relation so that the arm 33 may freely swing between its extreme positions. For the purpose of effecting the desired swinging movement of the arm 33, cam controlled rack and pinion mechanism individual to the take-out and transfer device is employed. This mechanism (Figs. 7 and 8) includes a pinion or gear segment 39 constantly meshing with a rack bar 40 which is adjustably connected to a slide block 41, the latter being mounted in slide-ways 42 for movement in a direction transverse to the path of travel of the carrier chain 21. A cam roll 43 mounted on the upper side of the slide block 41 is adapted for alternate engagement with two stationary cams 75 and 76 referred to hereinafter, so that through the rack and pinion mechanism oscillatory movement may be imparted to the take-out arm. The adjustable connection between the rack bar 40 and slide block 41 allows the operator to regulate and control the angle of inclination of the arm 33 in its extreme positions and the extent of swinging movement of said arm. The construction allowing such adjustment

70 consists of an adjusting screw 44 extending lengthwise of the slide block 41 and threaded through an upstanding lug 45 on the rack bar 40, said lug projecting into an upwardly opening way 46 in said slide block. By rotating the screw 44 the rack bar 40 is moved relative to the slide block transversely of the carrier block so that the extreme positions of the tongs 32 may be changed as desired. 75

The tongs 32 or grippers which supportingly engage the neck portions of the bottles or jars, correspond in number to that of the cavities in each finishing mold. In the present disclosure each finishing mold 80 has two cavities and, therefore, under normal operating conditions brings two finished bottles or jars to the discharge station "D" with each revolution of the machine. The tongs comprise a pair of jaws 47 suitably fixed to a pair of meshing gear segments 48 which are pivoted to a pair of shafts 49, the latter suitably mounted on the lower side of a pivoted head 50. Where two pair 85 of tongs are employed, as in the present application, one gear segment 48 of each pair is provided with a finger 51 extending into the hollow head 50, said fingers being connected together by a spring 52 which tends to yieldingly hold the tongs in operative position. 90

The tongs or grippers are periodically opened at regular time intervals by a cam 53 arranged within the head 50 between the fingers 51. This cam is connected to a short 100 shaft 54 (Figs. 10 and 11) which in turn is connected through a section of flexible shafting 55 to the main operating or rock shaft 56, the latter extending axially of the tubular arm 33 and journaled in bearings 57. 105 Oscillation of the shafts 54, 55, and 56 for the purpose of imparting corresponding movement to the cam 53 so that the jaws are opened periodically, is obtained by rocking a lever or finger 58 which is suitably secured to the inner end of the shaft 56 and extends through a radial slot 59 in the arm 33. The end walls of the slot 59 serve as stops limiting the extent of rocking movement of the finger 58 under influence of a spring 60. 110 This spring 60 (Figs. 6 and 7) is arranged so that it quickly moves to one of its extreme positions immediately after said finger has been moved past the dead center by other means presently to be described. While 115 the tongs are approaching the discharge station "D" they are held open by the cam 53. When the discharge station is reached, the finger 58 is reversed to shift the cam 53. This permits the spring 52 (Fig. 10) to actuate the tongs or grippers so that they may engage the necks of bottles or jars while the latter are in the finishing molds. The 120 said reversal of the finger 58 is effected by a cam actuated plunger 61 (Figs. 4, 7 and 9) 125

extending vertically through the carrier block 34. This plunger is normally held in its uppermost position by a spring 62, and in such position is adapted, as it approaches 5 the discharge station "D", to be engaged by a stationary cam 63 which is suitably supported on one of the guide rails 30 in proximity to the discharge station "D". This cam presses the plunger downward, causing 10 said reversal of the finger 58 and rocking of the shafts 54, 55 and 56 and permitting the spring 52 to close the tongs about the necks of articles in the mold. A plunger 64 spaced from the other plunger 61 also extends 15 vertically through the carrier block 34 and is held in its uppermost position by a coil spring 65. When the tongs, with the articles held thereby, reach the station "E", the plunger 64 is moved downward under influence 20 of a stationary cam 66 so that it moves the finger 58 downward (see Fig. 9) and rocks the shafts 54, 55, 56, whereby the cam 53 is operated to open the tongs at the station "E" for the purpose of placing bottles or jars upon the cross conveyor 18. The 25 spring 60 (Fig. 6) holds the finger 58 and cam in this last mentioned position until again actuated by the plunger 61, so that the tongs remain open until station "D" is 30 again reached.

By reference to Figs. 4 and 5 it will be noted that the tong carrying head 50 is adapted to occupy various angular positions relative to the take-out arm 33, this being 35 provided for by pivotal connection between the head and take-out arm. The construction involved (Figs. 3, 4, and 10) includes a pair of upstanding ears 67 on the upper side of the head 50 and ear 68 at the outer 40 end of the takeout arm, said ears being connected by a hinge pin 69. This hinge pin 69 is disposed parallel with the hinge pin 36 at the upper end of the take-out arm 33. For the purpose of limiting swinging movement 45 of the head 50 in one direction, relative to the take-out arm, an adjustable stop is provided, including an upstanding finger 70 on the head 50 and an adjustable set screw 71 at the lower end of the take-out 50 arm 33. By adjusting the screw 71, accurate alignment of the tongs or grippers with the finishing mold cavities may be insured. In this connection it is obvious by reference 55 to Fig. 5 that the head 50 must extend parallel with the upper end surface of the finishing mold in order to obtain proper engagement between the tongs and bottles.

The take-out and transfer arms (Figs. 1 and 5) are adapted to swing outwardly 60 relative to the path of travel of the carrier chain 21, as they approach the discharge station "D", so that the tongs may supportingly engage articles of glassware in the finishing molds. Later the arms are swung 65 in the opposite direction (Figs. 2 and 4) preparatory to placing the articles upon the cross conveyor 18 at the article releasing station "E". A cam 75 is secured to the upper side of the outer guide rail 30 in proximity to the discharge station "D" and is of such shape that it operates the rack and pinion mechanism in a manner to swing the arm 33 to the position shown in Fig. 5 and then, following removal of the articles from the finishing mold, allows the arm under its own weight to swing to a pendent position. A stationary cam 76 (Fig. 1) is secured to the inner guide rail 30 in such position that it causes a reverse operation of the rack and pinion mechanism resulting in swinging the take-out arm inwardly to approximately the position shown in Figs. 2 and 4. The take-out arm is maintained in such position until it has passed the cross conveyor 18 after which it may be lowered without interference from the latter.

The movements of the take-out and transfer devices in synchronism with the operation of the forming machine 15 is obtained through the provision of driving connection 90 between the machine and one of the shafts 23. The drive shaft 78 is driven by a ring gear 79 through bevel gears 80 and imparts rotary movement to the shaft 23 by way of a pair of meshing bevel gears 81 (Fig. 2). 95 A pinion 79^a rotates the ring gear. Suitable means (not shown) may be provided for changing the relative positions of the finishing molds 16 and combined take-out and transfer devices 20 as may be necessary 100 to obtain satisfactory operating conditions.

In operation, the forming machine 15, transfer mechanism 17, and cross conveyor 18 may be and preferably are operating continuously. A finishing mold 16 and combined take-out and transfer devices 20 are simultaneously brought to the discharge station "D". The cam 75 swings the take-out arm (Fig. 5) to a position in alignment with the corresponding finishing mold. 110 The tongs or grippers are now actuated so that they supportingly engage the necks of the articles of glassware enclosed in the finishing molds. As stated heretofore the cam 63 operates through the plunger 61 and the shafts within the take-out arm 33 to shift the cam 53 and permit the spring 52 to operate the tongs or grippers. It is understood that the tongs have been held open by the cam 53 during travel from the article releasing station "E" to station "D". Immediately upon proper engagement of the tongs with the bottles or other articles, the finishing mold 16 is opened by any conventional mechanism (not shown) leaving 115 the bottles entirely supported by said tongs. The cam 75 (Fig. 1) as stated heretofore, is of such shape that it allows the take-out arm to gradually assume a pendent position while moving away from the discharge 120 station "D". The cam 76 (Fig. 1) is of such shape that it causes the take-out arm to swing inwardly to approximately the position shown in Figs. 2 and 4. The take-out arm is maintained in such position until it has passed the cross conveyor 18 after which it may be lowered without interference from the latter.

station "D" toward the releasing station "E". As the take-out and transfer device approaches the station "E" (Figs. 1, 2, and 4) the stationary cam 76 operates through the rack and pinion mechanism 40 to swing the arm 33 into a substantially horizontal position so that the bottles assume positions over and in close proximity to the ware supporting reach of the cross conveyor 18. At the proper moment the cam 66 operates through the shafts 54, 55, and 56 and the cam 53, to open the tongs and release the articles. After the take-out and transfer devices have passed beyond the cross conveyor 18 on their way back to the discharge station "D" they are allowed to swing downwardly to a pendent position.

Modifications may be resorted to within the spirit and scope of the appended claims.

20. What I claim is:

1. In combination, a series of combined article take-out and transfer devices movable in a closed path past article engaging and releasing stations, said stations being disposed on opposite sides of the path, means for imparting continuous movement to the devices, each device including a pendent arm, article supporting means at the lower end of the arm, means for swinging the arm in a vertical plane at right angles to the path of travel of the series of devices for alternately placing said device in article engaging and releasing positions, and means for operating the article engaging means in timed relation to movement of the device.

2. In combination, a series of combined take-out and transfer devices movable in a closed path and in succession past article engaging and releasing stations, said stations arranged on opposite sides of said path of travel and at points spaced apart lengthwise of said path, each device including a pendent arm mounted for vertical swinging movement to alternately position its lower end on opposite sides of said path of travel, article supporting means at said lower end of the arm, cam mechanism for swinging said arm, and means in part controlled by swinging movement of the arm to operate the article supporting means.

3. In combination, a series of combined take-out and transfer devices movable in a closed path and in succession past article engaging and releasing stations, said stations arranged on opposite sides of the path of travel and spaced apart lengthwise thereof, and endless carrier supporting the devices, means for imparting continuous movement to the carrier, each device comprising a take-out arm having pivotal connection to the carrier and adapted to swing in a vertical plane below the carrier and in a plane transverse to said path of travel, article supporting tongs at the lower end of the arm, auto-

matic means for swinging the arm and tongs to opposite sides of the path of travel of the carrier and together with travel of the carrier alternately place the tongs at the article engaging and releasing stations, and means for operating the tongs in timed relation to movement of the arm.

4. In combination, a series of combined take-out and transfer devices movable in a closed path past a discharge station and an article releasing station, means for continuously moving said devices, each device comprising a pendent arm, article supporting tongs on the lower end of the arm, means for swinging the arm and tongs in a vertical plane transverse to said closed path to thereby alternately position the tongs at the article discharging and releasing stations, means for actuating the tongs in timed relation to movement of the arm, and adjustable means for changing the extent of swinging movement of the arm.

5. In combination, a series of combined article take-out and transfer devices movable in a closed path past article engaging and releasing stations, said stations arranged on opposite sides of the path, each device including a carrier block, an arm pivoted thereto for vertical swinging movement below the block in a plane transverse to said path, automatic means in part carried by the block for swinging said arm, a tong carrying head pivoted to the lower end of the arm, tongs on said head, and automatic means for actuating the tongs in timed relation to swinging of the arm.

6. In combination, an endless carrier movable in a horizontal plane, a carrier block mounted on said endless carrier, a take-out arm pivoted to and depending from said block, article supporting tongs at the outer end of said arm, means for imparting continuous movement to the carrier, means actuated by the movement of the carrier to swing the arm and tongs in a vertical plane transverse to the direction of travel of the carrier to thereby alternately position the tongs in article engaging and releasing positions, said positions arranged on opposite sides of the endless carrier, and means for actuating the tongs causing them to alternately engage and release articles.

7. In combination, an endless carrier movable in a horizontal plane, a carrier block mounted on said endless carrier, a take-out arm pivoted to and depending from said block, article supporting tongs at the outer end of said arm, means for imparting continuous movement to the carrier, means actuated by the movement of the carrier to swing the arm and tongs in a vertical plane transverse to the direction of travel of the carrier to thereby alternately position the tongs in article engaging and releasing positions, said positions arranged on opposite sides of

- the endless carriage, and means actuated by movement of the carrier and carrier block to cause the tongs to alternately engage and release articles.
- 5 8. In combination, an endless carrier movable in a substantially horizontal plane, a carrier block thereon, a take-out arm pivoted to and depending from said block, article supporting tongs on the outer end of said arm, said arm mounted for vertical swinging movement in a plane transverse to the direction of travel of the carrier block, cam controlled rack and pinion mechanism for swinging said arm between stations at opposite sides of the path of travel of the block and carrier, and means for actuating the tongs whereby they supportingly engage articles on one side of the carrier and release them on the other side thereof.
- 10 9. In combination, an endless carrier movable in a substantially horizontal plane, a carrier block thereon, a take-out arm pivoted to and depending from said block, article supporting tongs on the outer end of said arm, said arm mounted for vertical swinging movement in a plane transverse to the direction of travel of the carrier block, cam controlled rack and pinion mechanism for swinging said arm between stations at opposite sides of the path of travel of the block and carrier, and means for actuating the tongs whereby they supportingly engage articles on one side of the carrier and release them on the other side thereof.
- 15 10. In combination, an endless carrier movable in a substantially horizontal plane, a carrier block thereon, a take-out arm pivoted to and depending from said block, article supporting tongs on the outer end of said arm, said arm mounted for vertical swinging movement in a plane transverse to the direction of travel of the carrier block, cam controlled rack and pinion mechanism for swinging said arm between stations at opposite sides of the path of travel of the block and carrier, and means for actuating the tongs whereby they supportingly engage articles on one side of the carrier and release them on the other side thereof, and means for adjusting the rack and pinion mechanism to regulate the extent of swinging movement of said arm and tongs.
- 20 11. A combined take-out and transfer device comprising a carrier block, a depending take-out arm pivotally connected at its upper end to the lower side of said block by a horizontal pivot, a tong carrying head pivoted to the lower end of the arm, article supporting tongs on said head, means including a rack and pinion for swinging the arm in a vertical plane to thereby alternately place the tongs in article engaging and releasing positions, said rack being mounted to reciprocate on the carrier block and the pinion fixed to said arm concentric with said pivot, and means for actuating said tongs.
- 25 12. A combined take-out and transfer device comprising a carrier block, a depending take-out arm pivotally connected at its upper end to the lower side of said block by a horizontal pivot, a tong carrying head pivoted to the lower end of the arm, article supporting tongs on said head, means including a rack and pinion for swinging the arm in a vertical plane to thereby alternately place the tongs in article engaging and releasing positions, said rack being mounted to reciprocate on the carrier block and the pinion fixed to said arm concentric with said pivot, and means for actuating said tongs.
- 30 13. The combination of an endless carrier, means for causing it to travel in a horizontal closed path, a portion of said path being in the arc of a circle, article take-out and transfer devices connected to travel with said carrier and move in succession past article engaging and releasing positions, said article releasing position being disposed below said carrier and substantially at the axis of said arc, and means for actuating said devices and causing them to engage articles at said article engaging position, transfer them from said engaging position to the releasing position, and release them at said releasing position, said last mentioned means including mechanism for holding the article engaging portions of the holding devices at said releasing position during the release of the articles.
- 35 14. A combined take-out and transfer mechanism comprising an endless carrier movable in a horizontal closed path, a portion of said path being in the arc of a circle, the center of which is within the area bounded by said path, a carrier block on said carrier, a take-out arm pivoted to said block and depending therefrom, article supporting tongs on the lower end of said arm, means for swinging said arm from an article receiving position to a discharging station beneath said carrier and substantially at the axis of said arc and holding said arm in such position that said tongs are held at the discharging station during the travel of said block along said arc, and means controlled by the movement of said block for actuating the tongs to release an article at the discharging station.
- 40 15. Signed at Alton, Illinois, this 24th day of November 1930.
- 45 16. OLIVER C. K. HUTCHINSON.
